X-RAY CABINET OR SIMILAR ARTICLE

John A. Reynolds, White Plains, N. Y., and Edward B. Graves, Cleveland, Ohio, assignors to Picker X-Ray Waite Manufacturing Division, Inc., Cleveland, Ohio, a corporation of Ohio

Application February 15, 1956, Serial No. 40,178

Term of patent 7 years

(Cl. D26—5)

The single figure is a front perspective view of an X-ray cabinet or similar article, showing our new design. The back is plain or conventional and the opposite side not shown has substantially the same appearance as that shown in the figure. The dominant features of our new design are shown in solid lines in the drawing. Portions are diagonally lined to indicate transparency.

We claim:

The ornamental design for an X-ray cabinet or similar article, as shown and described.
